MARKER FOR CYLINDRICAL OBJECTS

Roy W. Redin and Samuel M. Behar, Chicago,
Ill., assignors to The Superior Type Company,
Chicago, Ill., a corporation of Illinois

Application May 17, 1943, Serial No. 487,232

16 Claims. (Cl. 101—40)

Our invention relates to a marking device for cylindrical objects, and has particular reference to a device having type or other printing means on a cylinder which prints or applies certain predetermined markings to the surface of cylindrical, hexagonal or cone-shaped objects, or an object of such shape that it can be rolled between the printing surface and the bed of the machine, such as small tubes, cans or the like.

Another and further object of our invention is the provision of a marking device in which the object to be marked is automatically fed into the machine on an inclined feeding tray and placed in printing position in the machine, and thereafter passed therethrough while being rotated at a speed equal to the peripheral travel of the type or printing face, thereby placing the proper marking, identification or the like, upon the surface of the cylindrical article without smearing or slipping so that the markings are plain, clear and presentable in appearance.

A further object of our invention is the provision of a marking device in which the objects to be marked are automatically fed into the machine and as they pass therethrough have the proper identification, marking and the like applied to the surface thereof without any attention on the part of the operator, and are automatically discharged from the opposite side of the machine after receiving the markings, identification, insignia or whatever indicia or marking it is desired to place on the surface thereof.

A still further object of the invention is the provision of an automatic feeding mechanism which picks the objects up from the feed tray and delivers them into proper printing position in the machine, with the feeding mechanism operating at a slightly lesser speed than the travel of the object to be marked so that the feeding mechanism, once it has performed the function of starting the object through the machine, does not in any way interfere with its movements through the machine and only performs the function of feeding the objects into the machine.

These and other objects of our invention will be more fully and better understood by reference to the accompanying sheets of drawings, and in which—

Figure 1 is an end elevational view of our improved machine taken on line 1—1 of Figure 2;

Figure 2 is a horizontal plan sectional view of the machine taken on line 2—2 of Figure 1;

Figure 3 is a vertical sectional view taken on line 3—3 of Figure 1; and

Figure 4 is an end elevational view more or 55 edges thereof are tracks 30, 30 set in peripheral

less diagrammatic in character illustrating the general operation of the machine.

Referring now specifically to the drawings, and in which like reference characters refer to like parts throughout, a base plate 10 is shown to which are secured end plates 11 and 12, respectively, in any approved manner as by bolts 13, 14, each of the end plates 11 and 12 having flanges thereon which extend inwardly of the machine 10 and toward each other. The base plate 10 and the end plates 11 and 12 in effect form the basic frame and housing of the machine. Mounted in the end plates 11 and 12 in suitable bearings is a transversely extending shaft 14 having a pulley 15 on the outer end thereof over which a belt 16 passes which, in turn, passes over a second pulley 17 mounted on a shaft 18. The shaft 18 is a part of an ordinary gear reduction mechanism of usual form enclosed in a housing 19, with a shaft 20 connected with suitable internal gears (not shown), having a coupling 21 thereon which engages with a second coupling 22 on the end of a motor shaft 23 leading to a motor 24 through which power is transmitted through the belt 16 and pulley 15 to the shaft 14.

A cylinder 25 is provided which has a hub portion 26 through which the shaft 14 extends, and which is keyed or otherwise secured to the shaft 14 so that the cylinder 25 is rotated by the shaft 14 during the operation of the device. Extending circumferentially around the cylinder 25 is a plurality of type channels 27, 27 secured to the cylinder 25 by means of screws 28, 28, these type channels having ordinary rubber type 29, 29 inserted therein. The type is of various sizes and kinds, with faces thereon of the letters of the alphabet or any other appropriate marking such as figures or the like, which may be desired or which may be necessary for the particular kind of work the machine is intended to perform. The type can be set in these channels in the ordinary manner, with spacers, slugs and the like, to form sentences or words such as may be desired, and which, during the operation of the machine, are brought into contact with the surface of the cylindrical object to be marked, as will be more fully described hereinafter. As shown in the drawings, the type bars extend around the periphery of the cylinder, but these bars may extend transversely or diagonally of the cylinder, or plates or dies may be used in the cylinder if desired and secured thereto in any approved manner.

Extending around the cylinder 25 at the outer

grooves formed in the edges of the cylinder 25, these tracks being made preferably of rubber or the like and slightly resilient so that they engage frictionally with the surface of the object to be marked. An arcuate shaped plate 31 is provided which has substantially the same curve contour as the surface of the cylinder 25 and spans the space between the end plates 11 and 12 and is secured thereto by means of screws 32, 32 and forms the bed for the machine. Spaced tracks 33, 33 are mounted on the inner face of the plate 31 and are secured thereto by means of rivets 34, 34 which have their heads countersunk into the tracks 33, 33 so that they do not interfere with the passage of the circular objects through the marking device. The tracks 33, 33 are preferably made of rubber which is highly compressible, closely approaching sponge rubber, so as to afford frictional engagement with the surface of the object to prevent its slipping during its progress through the machine, and also to compensate for slight irregularities in the sizes of the articles to be marked. The tracks are renewable by removing the rivets 34, 34 from the plate 31, so that as they become worn or lose their elasticity they can be easily and quickly replaced, thereby adding to the life of the machine and keeping it functioning in proper order.

The tracks 33, 33 at the ends 35 are tapered so as to allow the cylindrical objects to enter the space between the type 29, 29 and the cover 31, with compression taking place between the tracks 30 on the cylinder 25 and the stationary tracks 33 on the cover, so that the cylindrical objects are firmly held against longitudinal movement during the printing operation and are rotated as they travel through the machine.

For the purpose of feeding the cylindrical objects off the feeding tray and into printing position in the machine, a pair of triangular shaped pick-up members 36 and 37 are provided which rotate on the same axis of rotation as the cylinder 25 and have fingers 38, 38 at the apices of the triangular portions of the members 36 and 37 for engagement with the cylindrical objects to be marked. Collars 39, 39 are provided which fit against the outer faces of and are secured to the pick-up members 36 and 37 and over the hub portions of gear wheels 40 and 41, which are loosely mounted on the shaft 14 and rotate freely thereon. A pair of stub shafts 42 and 43 are mounted in the end plates 11 and 12, respectively with small gears 44 and 45 mounted thereon which are in mesh with the gears 40 and 41, respectively. Hub portions of the gears 44 and 45 are keyed or otherwise fitted to other gears 46 and 47, which in turn are in mesh with gears 48 and 49 mounted upon a shaft 14 and keyed to the shaft 14 so these gears 48 and 49 are rotated by the shaft 14 and in unison therewith. Power is transmitted from the shaft 14 through the gears 48 and 49 and 46 and 47 with gears 44 and 45 to the gears 40 and 41, which are fixed to the pick-up members 36 and 37. This train of gears forms, in effect, a series of reduction gears which cause the pick-up members 36 and 37 to rotate at a much slower peripheral rate of speed than does the cylinder 25, and at a slower speed than the travel of the object to be marked as it passes between the bed plate 31 and the cylinder 25, so that the fingers 38, 38 in effect do not keep up with the cylindrical object being marked after it is picked up by the fingers and carried to initial printing position. In effect the object to be marked is lifted off the pick-up fingers

at the initial stage of the marking operation and thereafter rolled by the tracks 30, 30 on the cylinder between the cylinder 25 and the bed plate 31. The pick-up member 36 has a plurality of pins 50, 50 extending laterally from the finger portions 38 for purposes hereinafter described.

Support members 51 and 52 are mounted on the intake side of the machine by means of bolts 10 53, 53 which pass through the support members 51 and 52 and into the flanges on the ends 11 and 12, respectively, with a transverse support member 54 extending across the ends of the members 51 and 52 which supports a feed tray or table 15 55. The feed tray 55 has its edges 56, 56 upturned and bent outward at right angles into lateral extensions 57, 57 which are secured to the flanges of the end plates 11 and 12 by means of screws 58, 58, which pass through spacer blocks 20 fitted against the flanges of the end plates 11 and 12. The feed tray 55 and supports therefor are inclined toward the machine so that the cylindrical objects fed into the machine will normally roll by gravity to the end of the feed tray 55. The inner end of the feed tray 55 extends inwardly adjacent the printing cylinder 25 and has a slight edge 59 to prevent the round objects from rolling in against the printing cylinder 25 and receiving markings from the type 25 which are not intended prior to the printing 30 operation.

A rocker bar 60 is provided which has shaft portions at each end mounted in the support members 51 and 52 and fingers 61 and 62 mounted thereon, the free ends of which are curved upward through slots 63, 63 in the feed tray 55 and into the path of circular objects, such as cans 64 or the like, being fed into the machine. A rod 65 is also mounted in the rocker bar 60, 35 with one end extending into the machine alongside of the pick-up member 36 and in the path of the pins 50, 50 mounted on the fingers 38, 38. The outer end 66 of the member 65 has a spring 40 67 mounted thereon which is anchored to the side 56 of the feed tray 55 by means of a screw 45 68, so that normally the fingers 61 and 62 are held in the path of the cans 64 and in front of the row of cans except one, as they are fed into the machine, as shown particularly in Figure 4.

An ordinary saturate ink roller 69 is mounted upon brackets 70 and 71 secured to a front cover plate 72 which has a base portion 73 and is held by a screw 74 to the base plate 10. The cover plate 72 spans the space between the inturned flanges on the end plates 11 and 12 and overlaps the edges of these flanges as shown in Figure 1. The ink roller has tracks 75 and 76 at each end thereof in engagement with the rubber tracks 30, 30 on the cylinder 25 which rotates the ink roller 69 during the operation of the printing cylinder 25, the inking portion of the ink roller 69 being adapted to contact the type mounted on the cylinder 25 during the operation of the device. At the rear of the machine an inverted U-shaped member 77 is mounted, the side portions of which extend vertically with its upper edges 78 and 79 being curved to receive the circular containers 64 after they pass over the cylinder 25, where they roll outward and are discharged from the machine after being printed or marked as desired by the type in the cylinder 25.

In operation, the type or impression material is placed in the type holders mounted in the periphery of the cylinder 25, in the approved combination desired on the containers, and the

containers are placed in the feed tray particularly as shown in Figure 4. Upon the machine being operated, the initial rotation will cause the pick-up members to rotate with the pins 50 in the fingers 38 engaging the end of the bar 65, tilting the rocker bar 60, causing the fingers 61 and 62 to be depressed, and allowing one of the containers, such as 64, to roll inward on the feed tray to the end thereof. The next succeeding fingers 38 pick up the container 64 and lift it upward to the inclined end 35 of the tracks 33 where the container is frictionally gripped between the tracks 30 and 33, and in effect is rolled from the intake side of the machine to the discharge side of the machine. It will be understood that the cylinder and the pick-up finger normally operate in a clockwise direction, so that this movement will cause the container to rotate in a counterclockwise direction, and while it is rotated the type in the bars come into contact with the wall of the container leaving an imprint thereon. The type in the meantime has passed over the saturate roller, from which ink has been transferred to the faces of the type before it is transferred to the containers. As the pick-up fingers lift one container into the initial printing position, the pins 38 engage the bar 65 thereby enabling another container to roll to the end of the feed tray adjacent the cylinder 25.

Due to the reduced gearing employed for driving the pick-up fingers, as soon as the receptacle is gripped between the tracks on the printing roll and the tracks 33 on the cover, the movement of the object being marked is faster than the travel of the pick-up fingers. The rate of travel of the receptacle is controlled by several factors, but primarily by the speed of rotation of the cylinder 25 and the circumference of the article to be marked. The peripheral speed of the cylinder 25 and the peripheral speed of the article being marked is the same. Each machine, therefore, must be designed to receive an object having a certain circumference, in order that the timing may be proper, and the type or marking elements be properly placed on the marking cylinder, with the reduction gears connecting the main shaft and the pick-up members being properly designed to control the speed of the pick-up members, all of which is well within the skill of those familiar with the art. When the object being marked reaches the opposite side of the roller it is discharged onto the receiving member 75, where it rolls out of the machine onto any suitable receiving table or into a package if desired. In this way the operation is continuous and can be repeated as long as the receptacles are kept on the feeding tray.

It will also be understood that in the form of the machine illustrated and described, only three sets of pick-up fingers are shown. Both the number and form of these fingers can be changed, if desired, depending upon the size of the machine and the particular form of type or articles which are to be marked.

We have also shown an ordinary saturate inking roller designed to supply a dye type of ink to the type. Other forms of inking mechanism can be used equally well, depending upon the surface to which the ink is to be applied, it being well known that various surfaces require various types and kinds of ink, and that some surfaces will not take some kinds of ink while others will, all of which is well known in the art of printing and marking.

While we have described more or less precisely

the details of construction, we do not wish to be understood as limiting ourselves thereto, as we contemplate changes in form and the proportion of parts and the substitution of equivalents as circumstances may suggest or render expedient without departing from the spirit or scope of the appended claims.

We claim:

1. Marking apparatus comprising in combination a frame, a rotatably mounted marking cylinder, an arcuate printing bed in spaced relation with the marking cylinder, the space between the said bed and the cylinder providing a channel for a rotatable article, tracks on the said cylinder extending circumferentially thereof, resilient tracks on the printing bed, a feeding tray extending radially from the printing cylinder and terminating adjacent thereto, and pick-up means adapted to transfer articles to be marked from the feeding tray into engagement with the tracks on the cylinder and printing bed, the speed of the pick-up means being less than the speed of the rotatable article.

2. Marking apparatus comprising in combination a frame, a rotatably mounted marking cylinder, an arcuate printing bed in spaced relation with the marking cylinder, the space between the said bed and the cylinder providing a channel for a rotatable article, tracks on the said cylinder extending circumferentially thereof, curved resilient tracks on the printing bed, an inclined feed tray, and a plurality of pick-up fingers adapted to pick up articles to be marked from one end of the tray and deliver said articles into the machine to be marked, the speed of travel of the pick-up fingers being less than the speed of travel of the rotatable articles.

3. Marking apparatus comprising in combination a frame, a rotatably mounted marking cylinder, an arcuate printing bed in spaced relation with said marking cylinder, whereby an arcuate channel is provided for rotatable articles, tracks on the said cylinder extending circumferentially thereof, resilient tracks on the printing bed, an inclined feed tray terminating adjacent the printing cylinder, rotatably mounted pick-up fingers mounted on the same axis as the marking cylinder and extending beyond the periphery thereof whereby articles to be marked are removed from the tray and delivered to printing position in the machine, the rate of travel of the pick-up fingers being less than the peripheral rate of travel of the marking cylinder.

4. Marking apparatus comprising in combination a frame, a rotatably mounted marking cylinder, an arcuate printing bed in spaced relation with said marking cylinder, whereby an arcuate channel is provided for the reception of rotatable articles, tracks on the said cylinder extending circumferentially thereof, resilient tracks on the printing bed, an inclined feed tray, and rotatably mounted pick-up fingers mounted on the same axis of the printing cylinder and extending beyond the periphery thereof whereby articles to be marked are removed from the tray and delivered to printing position in the machine, the speed of travel of the pick-up fingers being slightly less than the speed of travel of the object being marked as it passes through the marking cylinder.

5. Marking apparatus comprising in combination a frame, a rotatably mounted printing cylinder, an arcuate printing bed in spaced relation with said rotatably mounted cylinder, whereby a space is provided for the reception of rotat-

able articles, tracks on the said cylinder extending circumferentially thereof and resilient tracks on the printing bed the rotatable article being engaged between tracks on the said cylinder and the tracks on the said printing bed, an inclined feed tray, and rotatably mounted pick-up fingers mounted on the same axis as the printing cylinder and extending beyond the periphery thereof whereby articles to be marked are removed from the tray and delivered to printing position in the machine, the pick-up fingers being geared to travel at a slower speed than the articles to be marked.

6. Marking apparatus comprising in combination a frame, a rotatable marking cylinder, a semi-circular bed plate in spaced relation with the marking cylinder, resilient tracks on the said plate and on the said cylinder, an inclined feed tray, rotatable pick-up means mounted on the same axle as the marking cylinder, reduction gears connected to the said axle and pick-up means, whereby the said pick-up means rotates slower than the resultant peripheral speed of the article to be marked, and a discharged member over which the marked articles are discharged from said marking apparatus.

7. Marking apparatus comprising in combination a frame, a main shaft, a rotatable marking cylinder on said shaft, a semi-circular bed plate in spaced relation with the marking cylinder, resilient tracks on the said plate and on the said cylinder, an inclined feed tray, rotatable pick-up means mounted on the same shaft as the marking cylinder, reduction gears connected to the said shaft and pick-up means, whereby the said pick-up means rotates slower than the travel of the article to be marked over the printing surface, and a discharge member over which the marked articles are discharged from said marking apparatus.

8. Marking apparatus comprising in combination a frame, a main shaft on said frame, a rotating cylinder on said shaft, type holding bars mounted on said cylinder and extending circumferentially thereon in spaced relation with each other, removable type in said bars, a semi-circular printing bed mounted on said frame in spaced relation with the said cylinder whereby an arcuate space is provided between the cylinder and printing bed for the reception of rotatable articles, spaced resilient tracks on said bed, resilient tracks on the said cylinder in substantial register with the tracks on the said bed the rotatable articles being engaged by the resilient tracks on the said bed and the said cylinder, an inclined feeding tray having its inner end terminating adjacent the cylinder, and rotating pick-up fingers outside the end cylinder walls adapted to pick up articles to be marked and delivered into position to be engaged by the said tracks on the bed and cylinder, the rate of travel of the rotating pick-up fingers being less than the peripheral speed of the printing cylinder.

9. Marking apparatus comprising in combination a frame, a rotatable marking cylinder, a semi-circular bed plate in spaced relation with the marking cylinder, resilient tracks on the said plate and on the said cylinder, an inclined feed tray, rotatable pick-up means mounted on the same axle as the marking cylinder, reduction gears connected to the said axle and pick-up means whereby the said pick-up means rotates slower than the travel of the article being marked, a discharge member over which the marked articles are discharged from said marking apparatus, and means on the end of the said

tray whereby articles to be marked are held out of engagement with the marking cylinder.

10. Marking apparatus comprising in combination a frame, a rotatable marking cylinder, a semi-circular bed plate in spaced relation with the marking cylinder, resilient tracks on the said plate and on the said cylinder, an inclined feed tray, rotatable pick-up means mounted on the same axle as the marking cylinder, reduction gears connected to the said axle and pick-up means whereby the said pick-up means rotates slower than the article being marked, and a discharge member over which the marked articles are discharged from said marking apparatus, the end of the tray being upturned whereby articles to be marked are held out of engagement with the marking cylinder.

11. Marking apparatus comprising in combination a frame, a rotatable marking cylinder, a semi-circular bed plate in spaced relation with the marking cylinder, resilient tracks on the said plate and on the said cylinder, an inclined feed tray, rotatable pick-up means mounted on the same axle as the marking cylinder, reduction gears connected to the said axle and pick-up means whereby the said pick-up means rotates slower than the objects being marked, a discharge member over which the marked articles are discharged from said marking apparatus, and means whereby the objects to be marked are permitted to advance singly and successively on the said tray to pick-up position.

12. Marking apparatus comprising in combination a frame, a rotatable marking cylinder, a semi-circular bed plate in spaced relation with the marking cylinder, resilient tracks on the said plate and on the said cylinder, an inclined feed tray, rotatable pick-up means mounted on the same axle as the marking cylinder, reduction gears connected to the said axle and pick-up means whereby the said pick-up means rotates slower than the travel of the object being marked, a discharge member over which the marked articles are discharged from said marking apparatus, retarding fingers in the path of objects to be marked, and means operated by the pick-up means whereby the said retarding fingers are intermittently moved from the path of the articles to be marked on the said feeding tray.

13. Marking apparatus comprising in combination a frame, a rotatable marking cylinder, a semi-circular bed plate in spaced relation with the marking cylinder, resilient tracks on the said plate and on the said cylinder, an inclined feed tray, rotatable pick-up means mounted on the same axle as the marking cylinder, reduction gears connected to the said axle and pick-up means whereby the said pick-up means rotates slower than the article being marked, a discharge member over which the marked articles are discharged from said marking apparatus, a rocker bar, retarding fingers on said rocker bar extending into the tray, a spring secured to said tray to normally hold the retarding fingers in the path of the objects to be marked, and a finger on said rocker bar actuated by the pick-up means whereby the retarding fingers are moved out of the path of objects to be marked.

14. Marking apparatus comprising in combination a frame, a rotatable marking cylinder, a semi-circular bed plate in spaced relation with the marking cylinder, resilient tracks on the said plate and on the said cylinder, an inclined feed tray, rotatable pick-up means mounted on the same axle as the marking cylinder, reduction

gears connected to the said axle and pick-up means whereby the said pick-up means rotates slower than the article being marked, a discharge member over which the marked articles are discharged from said marking apparatus, a rocker bar, retarding fingers on said rocker bar extending into the tray, a spring secured to said tray to normally hold the retarding fingers in the path of the objects to be marked, and a finger on said rocker bar, and pins on said pick-up means for engagement with the finger on the rocker bar whereby the retarding fingers are intermittently turned out of the path of objects to be marked.

15. A marking machine comprising in combination a main frame, end plates secured to said main frame, a main operating shaft mounted in said end plates, a marking cylinder mounted on said main shaft, spaced resilient tracks on said cylinder, a curved bed plate in spaced relation with the said cylinder, resilient tracks on said plate in spaced relation with each other, rotatable pick-up members on said shaft, pins in one of said pick-up members extending laterally therefrom, a chain of reducing gears connecting the pick-up members with the said shaft whereby the pick-up members are rotated at a reduced rate of speed as compared with the rotation of the said shaft, an inclined feed tray terminating adjacent the marking cylinder, a rocker bar, fingers thereon which extend through the tray into the path of articles to be marked, a spring normally adapted to hold the said fingers in op-

erative position, and a second finger secured to said rocker bar and adapted to be engaged by the pins on the pick-up mechanism whereby the fingers on said tray are depressed out of the path of objects to be marked.

16. A marking machine comprising in combination a main frame, end plates secured to said main frame, a main operating shaft mounted in said end plates, a marking cylinder mounted on said main shaft, spaced resilient tracks on said cylinder, a curved bed plate in spaced relation with the said cylinder, resilient tracks on said plate in spaced relation with each other, rotatable pick-up members on said shaft, pins in one of said pick-up members extending laterally therefrom, a chain of reducing gears connecting the pick-up members with the said shaft whereby the pick-up members are rotated at a reduced rate of speed as compared with the rotation of the said shaft, an inclined feed tray terminating adjacent the marking cylinder, a rocker bar, fingers thereon which extend through the tray into the path of articles to be marked, a spring normally adapted to hold the said fingers in operative position, a limit stop co-acting with the said spring to limit the upward movement of the said fingers, and a second finger secured to said rocker bar and adapted to be engaged by the pins on the pick-up mechanism whereby the fingers on said tray are depressed out of the path of objects to be marked.
